[57] **CLAIM**

The ornamental design for a wall mounted horizontal support frame, as shown and described.

DESCRIPTION

FIG. 1 is a top plan view of a wall mounted horizontal support frame, showing our new design;

FIG. 2 is a front elevational view thereof, the rear and bottom surfaces being unornamented; and

FIG. 3 is a side elevational view taken from the left of

FIG. 2, the side opposite being a mirror image thereof.
